UNITED STATES PATENT OFFICE

2,655,917

TOE PROTECTOR

Isadore Kiwad, Westwood, N. J.

Application July 17, 1951, Serial No. 237,119

2 Claims. (Cl. 128—153)

1

This invention is directed toward an improved construction for toe protector devices adapted to be worn upon the feet to protect the toes, it being one of the principal objects of my invention to provide a toe protector device of the class described which shall represent a modified and improved form of construction over that disclosed and claimed in my copending application Serial No. 65,250 now Patent No. 2,593,767, filed December 14, 1948 for Toe Protector.

Another object of my invention is to provide a toe protector device of the class described which shall be characterized by the simplicity of its construction and the relatively inexpensive cost of manufacture, as well as the ease and facility with which the user thereof may effectively apply the device whereby it acts as an insulator between the toes.

Other objects and advantages of the invention will become apparent from the description to follow or will hereinafter be more particularly pointed out.

In the accompanying drawing,

Fig. 1 is a perspective view of a blank or strip of material from which the toe protector device of my invention is formed;

Fig. 2 is a perspective view thereof after the blank has been acted upon in accordance with my invention;

Fig. 3 is a perspective view of the device shown in Fig. 2 but illustrating the position of certain portions thereof after they have been manually moved to effective position;

Fig. 4 is a perspective view of the underside of a foot showing my toe protector as shown in Fig. 3, effectively positioned on the foot;

Fig. 5 is a perspective view of the foot shown in Fig. 4, but as viewed from above, looking down on the toes;

Fig. 6 is an elevational view of a processed blank similar to the Fig. 2 form, but showing a modified construction thereof;

Fig. 7 is a view similar to Fig. 2, but of the modified form of invention shown in Fig. 6; and

Fig. 8 is a top edge plan view of the Figs. 6 and 7 form of invention and showing the positioning of certain portions thereof for effective use.

As noted in my said copending application Serial No. 65,250 now Patent No. 2,593,767, my invention is concerned with providing relief in foot ailments as well as a means for minimizing the danger of infection by spacing apart the adjacent surfaces of the toes of the foot and introducing a buffer therebetween. In the pres-

2

ent invention the applicant has greatly simplified the construction thereof and the manner of its effective use.

Referring now in detail to the drawings and more particularly to Figs. 1 through 5 thereof, I provide a blank 10 consisting of a strip of suitable soft material such as, for example, felt, cotton, rayon, wool, plastic, fabric and the like of suitable thickness, which, as noted, is rectangular in shape. I have found that satisfactory results are obtained when the thickness of the material lies within the range of from approximately $\frac{1}{16}$ of an inch to approximately $\frac{1}{8}$ of an inch. The blank 10 is provided with a series of four substantially lengthwise intermittent slotted portions 11, 12, 13 and 14, starting from one end 10a of said blank 10 and disposed between the top and bottom edges 10b and 10c respectively of the said blank 10. There is thus provided a corresponding series of unslotted portions 11a, 12a, 13a and 14a in the blank 10. There is also provided at the front end of each slit 12, 13 and 14, (counting the edge 10a as the front end of the blank for the purpose of clarification) a transverse slit 15 communicating with the said slits 12, 13 and 14.

It is thus seen from the above description that there is provided a longitudinal continuous base portion 16 running the entire length of the blank 10, and a series of movable finger or toe spacer members 17, 18, 19 and 20. It is further noted that, as above described, I have produced a toe protector device in which there is no waste material, since the entire blank 10 is fully utilized for effective use as will soon be described. This makes for relatively low expense of manufacture. It is noted that the blank 10 and the slits 11 to 14 as well as the slits 15 may be provided in a single cutting die operation from a continuous strip of material to further lessen the cost of manufacture.

To effectively use the toe protector of the present invention the spacer members 17, 18, 19 and 20 are first manually raised from their original position shown in Fig. 2 to the position shown in Fig. 3 after which the base portion 16 is positioned on the underside of the foot in the hollow area between the ball of the foot and the toes with the base portion adjacent the forward end 10a lying at the base of the big toe T and the spacer portions between adjacent toes. Thus, for example, the spacer 17 is interposed between the big toe T and then to A; the spacer 18 is disposed between the toes A and B; the spacer 19 is disposed between the toes B and C;

and the spacer 20 is disposed between the toes C and D.

In Figs. 6, 7 and 8 I have shown a modified form of my invention in which there is provided a rectangular blank 30 similar in form and function to that of the blank 10 except that it is relatively wider. As in the case of the blank 10, I provide a series of longitudinal slits 31, 32, 33 and 34 and connecting transverse slits 35, similar in function and purpose to the slits 11 through 15 of the Figs. 1 to 5 form of my invention. It is noted that there are a series of unslotted portions 31a, 32a, 33a and 34a, providing spacer members 37, 38, 39 and 40 and a common base portion 41. In this form of my invention to prepare the toe protector for effective use, instead of manually raising the spacer members 37 to 40 as previously explained in connection with the spacer members 11 to 14, they may be rotated from their original position shown in Fig. 7 to the position substantially at right angles to the plane of the base 41 as best seen in Fig. 8. The spacers 37 to 40 may then be placed between the toes and the base member 41 disposed as shown in Fig. 4.

I have found that satisfactory results are obtained when the slits 11, 12, 13, and 14 of the Figs. 1 through 5 form of my invention are disposed approximately midway between the longitudinal edges of the blank 10. In the Figs. 6 to 8 form of my invention, satisfactory results are obtained when the slits 31, 32, 33 and 34 are disposed at a point approximately one third of the distance between the longitudinal edges of the blank 30.

Although I have described my invention in specific terms, it will be understood that variations may be made in size, shape, materials and arrangement without departing from the spirit and scope of the invention as claimed.

I claim:

1. As a new article of manufacture, a toe protector formed from a normally flat strip of relatively soft and resilient material having top and bottom longitudinal edges, and first and second

end edges, a plurality of longitudinal slotted portions in said strip of a pre-determined length substantially equal to the distance between the toes of a user, disposed between said top and bottom longitudinal edges, starting from said first end edge and intermittently spaced along the length of said strip, terminating at a point spaced from said second end edge, a plurality of transverse slotted portions in said strip, starting from said top longitudinal edge and extending downwardly a distance substantially equal to the distance between the top and bottom surfaces of the toes of said user, to direct communication with said longitudinal slotted portions to form a longitudinal base portion and a plurality of manually movable toe space members for the purposes set forth.

2. As a new article of manufacture, a toe protector formed from a strip of felt having top and bottom longitudinal edges, and first and second end edges, a plurality of longitudinal slotted portions in said strip of a pre-determined length substantially equal to the distance between the toes of a user, disposed between said top and bottom longitudinal edges, starting from said first end edge and intermittently spaced along the length of said strip, terminating at a point spaced from said second end edge, a plurality of transverse slotted portions in said strip, starting from said top longitudinal edge and extending downwardly a distance substantially equal to the distance between the top and bottom surfaces of the toes of said user, to direct communication with said longitudinal slotted portions to form a longitudinal base portion and a plurality of manually movable toe space members for the purposes set forth.

ISADORE KIWAD.
